UNITED STATES PATENT OFFICE.

JOSEPH HARRY GRUVER, OF BALTIMORE, MARYLAND, ASSIGNOR TO HOLLOW BALL COMPANY, INCORPORATED, OF BALTIMORE, MARYLAND, A CORPORATION OF MARYLAND.

MANUFACTURE OF HOLLOW METAL BALLS.

Application filed October 3, 1921. Serial No. 505,083.

To all whom it may concern:

Be it known that I, JOSEPH HARRY GRUVER, a citizen of the United States, and resident of Baltimore, Maryland, have invented certain new and useful Improvements in the Manufacture of Hollow Metal Balls, of which the following is a specification.

This invention relates to the manufacture of hollow metal balls and has for its general object, improvements in methods and apparatus used in the manufacture of such balls as well as improvements in the balls themselves.

15 In my Patents Nos. 1,278,914 and 1,278,915, I have disclosed a method of making hollow metal balls, which comprises in general, forming an approximately spherical shell from a flat metal blank by a series of forming operations, and then rolling and spinning the shell thus formed under pressure in relatively, movable, cooperating, circular grooves in the faces of opposed discs, to close the hole in the shell and improve its sphericity. The invention of the present application relates to certain improvements in the method and apparatus described in those earlier patents.

30 One of the objects of the present invention is to devise more efficient closing grooves. I have discovered that the shape of the closing grooves has an important bearing on the efficiency of the closing operation and have found it advantageous so to form this groove that the shell contacts with it at two points only. To attain this result, I make the rolling groove with outwardly diverging sides, of such form that the two points of contact are substantially below the mouth of 35 the groove even at the start of the closing operation, thus preventing the cutting of the shell. When a shell is rolled under pressure within a circular groove of this meridional section, the groove imparts a gyrating movement to the shell and is highly efficient in working and spinning the metal of the shell, to close the hole or holes left after the forming operation, knit the metal into a substantially homogeneous shell, and size the ball.

40 In my earlier patents, I have described making balls from a blank of flat metal. For small balls, that is for balls less than about 1 inch in diameter, this method is

quite satisfactory, but for the larger sizes, 55 the number of forming operations, preliminary to rolling and closing, and the number of annealing and rolling operations must be increased. Moreover, where a nicely balanced ball must be obtained, as for certain 60 types of valves, it is difficult to obtain a perfect balance in the larger sizes when starting from a flat blank. It is, therefore, a further object of this invention to improve and simplify the manufacture of the larger 65 size balls and to make a more perfectly balanced ball. I attain this object by starting out with a trimmed tubular blank and partly close the two ends by forming or pressing operations preparatory to rolling. After 70 rolling and closing, the finished product thus has two diametrically opposed poles where the metal is knitted together and the ball is more perfectly balanced than if it had but a single point of closure. In thus making 75 hollow balls from tubular blanks, I have also found it advantageous to taper the side walls from the central zone toward the ends before the forming operation. By doing this the forming operations are more easily performed, smaller holes are made, the relatively thick wall at the center of the blank prevents buckling during forming, and I am enabled to obtain substantially uniform wall thickness with a minimum of rolling. 80

85 In order that the invention may be more clearly understood, certain preferred embodiments of it are shown in the accompanying drawing, in which:—

Figure 1 is a longitudinal section through 90 a tubular blank, which is cut and trimmed from tubular stock.

Fig. 2 is a similar view of this blank converted into substantially spherical form, but with openings at opposite sides by means of 95 the dies shown in Figs. 3^a and 3^b.

Fig. 3 is a section through a closed ball which results from taking the ball form of Fig. 2 and closing its openings in accordance with the present invention. 100

Fig. 3^a and Fig. 3^b are vertical sections through the preliminary forming dies showing two steps in the forming operation.

Fig. 4 is a side view of a rolling machine. Fig. 5 is a detail sectional view of one of 105 the ball rolling plates with its grooves.

Fig. 6 is a view in the nature of a diagram of the shape of a pair of closing grooves.

Fig. 7 is a view similar to Fig. 6 but showing a modified form of groove.

In carrying out the invention I take metal tubing, the wall of which is substantially of the same thickness throughout, and from this I cut a section, and at the same time edge and taper it from its center towards either end, as shown at 11 in Fig. 1. This tapered section of tubing is then placed between forming dies, shown in Figs. 3^a and 3^b, which are mounted in a suitable machine, and with one or more pressing or forming operations, according to the size of the shell, I obtain a blank or shell which is round, as shown in Figs. 2 and 3^b, having two small holes 12 opposite each other. The shells are subjected to annealing operations, repeated as may be necessary.

This shell or ball with two holes is next placed in specially formed grooves of a machine illustrated generally in Fig. 4 for closing and sizing. The grooves are formed in the faces of opposing discs, the upper one of which is adjustable towards and from the lower one by hand wheel 3 through gearing 4, and the lower may be rotated through mechanism illustrated in Fig. 4. The holes are closed and the ball is sized by a rolling and spinning action, and this action is given under gradually increasing pressure, as the operation progresses. At first the upper die or plate 2 is raised to permit the rough ball shapes to be introduced into the groove 1, and then by turning the hand-wheel 3 at the upper portion of the machine in the proper direction this upper die is lowered through the gearing, to bear upon these balls. The lowering movement may be comparatively rapid at the beginning of the pressure on the balls, but as the size is reduced and the hole closed, the lowering speed must be slowed down. The relative position of the plates and the size of the balls is indicated on a dial ring 5 and pointer 6 at the top of the machine.

As shown in Fig. 6, the configuration of groove 1 is specially formed. Viewed in cross section, it is made up of segments of two circles. From *a* to *b*, Fig. 6, the arc is struck from *c* as a center, and the diameter here is, say, .685 of an inch. The bottom of the groove, i. e., the part lying between the points *b*—*b*, is struck on a radius (giving a diameter of, say, .625) from center *d*. The rough ball shape, when first introduced into this groove, is represented approximately by the dotted circle *e*. It will thus be seen that from the mouth of the groove to substantially half way to the bottom thereof the radius is larger than the shell or ball when placed in the groove. From substantially half the depth to the bottom of the groove, the radius is substantially that of the radius of the ball when the operation is completed.

In these grooves of the upper and lower

discs, a ball or shell has a four point bearing, the points of bearing being located in a plane nearly half depth of the groove when the ball or shell is placed in the grooves although the ball does not touch the bottom of the grooves. The two points of contact in each groove are less than 180° apart. When pressure is exerted on the shell or ball by the grooved discs between which the balls are located, owing to the tapering of the shell and the special configuration of the groove, a movement of metal starts from desired parts of the wall, and goes towards the holes in such a manner that the holes are closed to the full thickness of the wall, the particles of metal tightly knitting together, and the wall of the ball being thickened to the desired degree, and I produce a ball that is of the same strength at all parts and perfectly balanced.

I anneal the shell or ball before placing it in the grooves and do not confine myself to one rolling or annealing.

The groove for sizing the ball and closing the openings therein may be of the form shown in Fig. 7, in which, as appears in cross section in said figure, from substantially half way to the bottom to the mouth the walls are formed on lines diverging outwardly, and from a point substantially half way of the depth of the groove to the bottom thereof, the wall follows a segment of a circle, the radius of which is substantially that of the ball when the operation is completed. When the ball comes from the closing and sizing grooves it may not be perfectly spherical. As a finishing operation, I place it between the shallow finishing grooves 7 which grooves are circular in cross-section cut on a circle of larger diameter than the ball so that each groove contacts with the ball at one point only.

By the use of a closing groove of the configuration described or its equivalent the balls are caused to constantly change as to the position of their axis of rotation so that they do not rotate about an axis always disposed horizontally. This would be undesirable because then the balls would roll only on their top and bottom portions like a wheel turning about a horizontal axis. With the four point bearing however, in which two of the points are travelling faster than their companion points by reason of their greater distance from the center of rotation the ball form is given what may be called a gyrating movement and all parts are brought under the action of the walls of the groove causing the metal to flow or move from all directions towards the axis of the opening or openings so that eventually the ball is completely closed. The invention is not limited to the use of rotating discs as other forms of grooved members may be employed to give the ball its universal rotary

displacement so that all parts will be acted on.

I am aware that prior to my invention, it has been proposed to make a shell from metal tubing with holes at opposite points to receive a rod or baluster, but in that proposal a tube tapered to its ends was not suggested, neither was a completely closed hollow sheet metal ball a part of this prior proposal. I am also aware of the Letters Patent of the United States granted to Brandt No. 207,158, August 20, 1878, which discloses the revolution of open shells or balls in grooved plates under pressure in order to smooth or polish the surface of said shells, the grooves being semi-circular in cross section, the object there being to obtain a bearing on as much of the surface of the shell or ball as possible.

20 So far as I am aware, I am the first to close a hole or holes in a shell or ball by revolving it under pressure in grooves, and to accomplish this most efficiently I employ grooves of the peculiar configuration disclosed.

The terms one, two, and four-point contact as used in the specification and claims, are not to be construed in a strictly geometrical sense. The shells and the closed balls have a slight resiliency so that when under pressure they are slightly flattened at the points of contact and thus these "points" are in fact small areas of contact.

I claim:

35 1. The herein described method of making hollow balls, consisting in forming a blank from a section of metal tubing by tapering it from its center towards either end, subjecting such blank to reforming operations in forming dies, to form an incompletely closed, approximately spherical shell and then revolving said shell under pressure in grooves, until the holes are closed to the full thickness of the wall, the metal tightly knitted, and the wall thickened to the desired degree.

2. Apparatus for rolling hollow metal shells or balls to close their openings and size them, comprising two grooved members having relative movement, the groove in each member having its bottom curved on a radius substantially equal to the radius of the finished ball, said bottom curve starting well down within the groove, and the concave wall from the top of this bottom curve to the mouth of the groove being on a curve whose radius is greater than the radius of the said bottom curve, substantially as described.

60 3. Apparatus for rolling hollow metal shells or balls to close their openings and size them, comprising two grooved members having relative movement, the groove in each member having its bottom curved on a radius substantially equal to the radius of

the finished ball, said bottom curve starting substantially half way within the groove, and the walls of the groove from the mouth of this bottom curve to the top of the groove being along lines diverging outwardly. 70

4. Apparatus for rolling and sizing hollow metal balls, comprising the combination of two grooved members having relative movement, the groove in each member having side walls which diverge outwardly from a zone substantially half-way between the mouth and bottom of the groove, and making only a two-point contact with the ball, below the mouth of the groove. 75

5. The method of making hollow metal balls which comprises forming an approximately spherical incompletely closed shell, and imparting a gyrating rolling motion to said shell under pressure within an open groove which contacts with the shell at two points only, to close the opening or openings in the shell and reduce it to size, the points of contact being below the mouth of the groove and less than 180° apart. 80

6. The method of making hollow metal balls which comprises forming an approximately spherical incompletely closed shell, and imparting a gyrating rolling motion to said shell under gradually increasing pressure within an open groove which contacts with the shell at two points only, to close the opening or openings in the shell and reduce it to size, the points of contact being below the mouth of the groove and less than 180° apart. 85

7. The method of making hollow metal balls which comprises forming an approximately spherical incompletely closed shell, and imparting a gyrating rolling motion to said shell under pressure within two mutually opposed grooves, each of which makes only a two-point contact with the shell below the mouth of each groove, to close the opening or openings in the shell and reduce it to size. 90

8. Apparatus for rolling and sizing hollow metal balls comprising the combination of a disc having in its face a circular groove with outwardly diverging side walls contacting with each ball below the mouth of the groove at two points only, these points being less than 180° apart, and means cooperating with said disc to roll the balls within the groove under pressure. 115

9. Apparatus for rolling and sizing hollow metal balls comprising the combination of two discs provided in their faces with cooperating ball-receiving circular grooves having outwardly diverging side walls, each groove making only a two-point contact with the ball below the mouth of each groove, means for imparting relative rotation to said discs, and means for exerting pressure between said discs to compress the balls. 120

10. Apparatus for rolling and sizing hollow metal balls comprising the combination of two discs provided in their faces with cooperating ball-receiving circular grooves having outwardly diverging side walls, each groove making only a two-point contact with the ball below the mouth of each groove, means for imparting relative rotation to said discs, means for moving said 10 discs toward each other to compress the balls, and means for indicating the relative position of the discs.

11. A balanced metal ball having walls of substantially uniform thickness and made 15 from a piece of tubing by tapering it from its center towards its ends, forming it into an approximately spherical, incompletely closed shell, and working the shell under pressure to close the openings therein and 20 knit the metal.

12. The method of making hollow balls,

consisting in forming a blank from a section of metal tubing by tapering it from its center toward either end, subjecting such blank to forming operations to provide a 25 ball having openings therein, and mechanically flowing together the metal surrounding said openings to close the same and provide a ball having seamless, homogeneous 30 walls, and simultaneously shaping said ball during the metal flowing operations.

13. Apparatus for rolling and sizing hollow metal balls comprising the combination of a disc having in its face a circular groove with outwardly diverging side walls making only a two-point contact with the balls below the mouth of the groove, and a second grooved disc cooperating with the first disc to roll the balls within the grooves under pressure.

In testimony whereof, I affix my signature.

JOSEPH HARRY GRUVER.
